Attorney

UNITED STATES PATENT OFFICE.

JAMES POLICK WILLIAMS, OF COVINGTON, KENTUCKY.

OILING SYSTEM FOR RAILWAY-CAR JOURNALS.

1,206,967.

Specification of Letters Patent.

Patented Dec. 5, 1916.

Application filed July 20, 1916. Serial No. 110,830.

To all whom it may concern:

Be it known that I, JAMES P. WILLIAMS, a citizen of the United States, residing at Covington, in the county of Kenton and State of Kentucky, have invented certain new and useful Improvements in Oiling Systems for Railway-Car Journals, of which the following is a specification.

This invention relates to new and useful improvements in oiling systems for railway car journals and has for its primary object to provide a means for automatically oiling the wheel axles of the cars or coaches when the train is in motion, to cut off the supply of oil when the train is at a stop or not in motion and for regulating or controlling the amount or quantity of oil supplied to the axle journals in accordance with the speed of the train.

With the foregoing and other objects in view that will appear as the nature of the invention is better understood, the same consists in the novel features of construction, combination and arrangement of parts illustrated in the drawings and more particularly pointed out in the appended claims.

In the accompanying drawings:—Figure 1 is a diagrammatic view of the frame and trucks of a railway car or coach, illustrating the application of my invention. Fig. 2 is a side elevation of Fig. 1. Fig. 3 is a side elevation of the valve and governor for controlling or regulating the flow of the oil to the axle journals in accordance with the speed of the train. Fig. 4 is a central vertical transverse section of Fig. 3. Fig. 5 is a detail view, partly in section, showing more particularly the spring controlled check valve for cutting off the supply of oil to the axle journals when the car is not in motion and Fig. 6 is a similar view of another form of check valve that may be used to accomplish the same purpose.

Referring to the drawings for a more particular description of the invention and which drawings are for illustrative purposes only and are therefore not drawn to scale, I indicates the truck frame, 2 the wheels and 3 the axles of a railway car or coach, these parts being of the ordinary or usual construction and forming no part of this invention.

In carrying out my invention, an oil tank, preferably of cylindrical form, is supported in any desired manner beneath the car body, as shown, at one side of the truck frame.

This tank is connected with the main oil distributing pipe 5 which extends longitudinally of the track beneath the car body, by a lateral branch pipe 6. The ends of the pipe 5 are connected with the transverse pipes 7 which in turn are connected with the branch pipes 8, the pipes of each pair of which extend forwardly and rearwardly in opposite directions longitudinally of the car and terminate in the depending portions 9 which communicate with the axle journals 10.

The oil tank is connected with the air brake and steam pipes 11 and 12, respectively, which also extend longitudinally of the track beneath the car body, by the lateral branch pipes 13 and 14 which communicate with opposite ends of the oil tank, as shown, and the oil in the tank may be maintained under the desired pressure by either air or steam, as desired.

The lateral branch oil pipe 6 comprises the inner upper and the outer lower horizontal sections 15 and 16, respectively, which communicate with the upper and lower compartments 17 and 18 of the valve casing 19. The horizontal wall or partition 20 dividing the valve casing into two compartments, is formed with a central downwardly flared or tapered valve opening 21 adapted to be closed by the correspondingly tapered end, as 22, of the valve 23, slidably mounted on a vertical shaft or rod 24, supported beneath the car body by the depending bracket 25.

When the car is not in motion, the valve opening in the casing is closed by the valve 23, as shown, but when in motion the valve is raised from its seat to a greater or less extent, depending on the speed of the train and allows the oil or lubricant to flow through the valve opening in the wall or partition 20 and thence through the oil distributing pipes above described to the journal boxes to lubricate the wheel axles, as will be apparent upon inspection.

In the present disclosure, the governor comprises an upper collar 26 which is rigidly connected with the shaft 24 and a lower collar 27 which is slidable on the shaft and engages the lower end of the valve 23. The collars 26 and 27 are connected by the flat bow-shaped springs 28 provided at intermediate points with the weights 29 and it is apparent upon inspection that when the shaft 24 is rotated, the springs 28 will spread farther apart and through the medium of

the collar 27 which will be caused to ascend on the shaft 24, raise or lift the valve 23, the degree or extent which the valve is raised from its seat and the quantity or amount of oil thus allowed to flow through the valve opening and thence through the oil distributing pipes to the axle journals, depending entirely on the speed of the train. The governor shaft 24 is geared with one of the axles of the car, by a belt 30 passing over the grooved belt wheels 31 and 32, respectively, on the axle and the lower end of the governor shaft.

The depending portions 9 of the branch oil pipes 8 are equipped with the horizontal spring-controlled check valves 33 to cut off any flow of oil remaining in the oil pipes when the car is at rest and the supply cut off from the oil tank by the valve 23, whereby flooding of the axle journals when the car is not in motion is obviated, it being obvious that no oil is consumed when the train is not in motion and that the greater the speed of the train the greater the amount or quantity of oil required to lubricate the wheel axles, or vice versa.

If desired, I may employ a vertically arranged check valve 34 of the character shown in Fig. 6, instead of the form shown in Fig. 5.

From the foregoing description taken in connection with the drawings, it is thought that the construction and operation of this invention will be readily understood without requiring a more extended explanation.

Various changes in the form, proportions and minor details of construction may be resorted to without departing from the principles or sacrificing any of the advantages of this invention as defined in the appended claims.

Having described my invention, what I

claim as new and desire to secure by Letters Patent, is:—

1. In an oiling system for railway car axle journals, an oil tank mounted beneath the car, oil distributing pipes, including a lateral branch pipe connected with the oil tank, between the oil tank and the axle journals, a valve in the lateral branch pipe for cutting off the supply of oil from the tank when the car is not in motion, means for maintaining the oil in the tank under pressure and a governor geared with one of the car axles for lifting the valve from its seat to a greater or less extent as the speed of the car increases or decreases, and thus regulate the amount of oil allowed to flow through the valve opening to the distributing pipes.

2. In an oiling system for railway car axle journals, an oil tank mounted beneath the car and connected with the air brake pipe and main steam pipe of the car whereby the oil in the tank is maintained under a constant pressure, oil distributing pipes, including a lateral branch pipe communicating with the oil tank, for conducting the oil to the axle journals, a valve in the lateral branch pipe for cutting off the supply of oil from the tank when the car is not in motion and a governor geared with one of the car axles for lifting the valve from its seat to a greater or less extent in accordance with the speed of the car and thus regulate the amount of oil allowed to flow through the valve opening to the axle journals via the distributing pipes.

In testimony whereof I affix my signature in the presence of two witnesses.

JAMES POLICK WILLIAMS.

Witnesses:

FRANK FLAKE,
JOE MUELLER.
